(Cl. D15—8)

To all whom it may concern:

Be it known that we, Fensky Conroe Terzia, Jr., and Mary Ann Terzia, citizens of the United States, residing at Monroe, Ouachita County, Louisiana, have invented a new, original, and ornamental Design for an Infant Feeding Chair, of which the following is a specification, reference being made to the accompanying drawing, forming a part thereof.

We claim:

The ornamental design for an infant feeding chair, substantially as shown.

FENSKY C. TERZIA, JR.
MARY A. TERZIA.
